UNITED STATES PATENT OFFICE

ENOS A. STEWART, OF CANTON, OHIO

BRICK-VENEEERING MACHINE

Application filed November 2, 1927. Serial No. 230,502.

The invention relates to veneering of brick and the like and more particularly to a machine for forming brick in which the clay column issuing from the machine is provided upon some or all of its faces with a veneering of clay or the like.

The object of the improvement is to provide a machine which may comprise a brick machine of any usual and well known construction having combined therewith an apparatus for placing a veneering of clay or the like upon some or all of the faces of the clay column formed by the brick machine, means being provided for maintaining a uniform pressure upon the veneering substance.

An embodiment of the invention is illustrated in the accompanying drawing, in which

Figure 1 is a longitudinal sectional view through a machine embodying the invention;

Fig. 2, a section on the line 2—2, Fig. 1, and

Fig. 3, a section similar to Fig. 2, showing a form of the apparatus designed to apply a veneer upon all four sides of a clay column.

Similar numerals refer to similar parts throughout the drawing.

The apparatus may include a brick machine of any usual construction comprising the cylinder 1 having the feed hopper 2 at its rear end for receiving clay, shale or the like, and having the auger 3 for feeding the clay forward and through the column die 4 in a column as indicated at 5.

This much of the machine may be of any well known construction adapted for forming a clay column. The invention pertains to the placing of a veneer of clay or other suitable material upon some or all of the faces of the clay column thus formed.

The apparatus for forming the veneer comprises generally means for feeding clay or other suitable material to and around some or all sides of the clay column and means for placing a uniform pressure upon the veneering material as the same is fed to the clay column.

This apparatus may comprise a small auger machine located adjacent to the brick machine above described, and comprising the cylinder 6 having the feed hopper 7 and auger 8 for

conveying the veneering material into the vertical chamber 9, the lower end 10 of which is located adjacent to the column die 4 whereby the clay column as it issues from the die will pass therethrough.

The sides of this lower portion 10 of the chamber are preferably inclined downward toward the column as indicated at 11. As shown in Figs. 1 and 2, the device is arranged to provide a veneering upon the top and two side faces of the column by providing the raised bottom 12 in the lower portion of the chamber 11, upon which the clay column is arranged to slide.

If it is desired to coat the bottom surface also of the clay column with a veneer, the lower portion of the chamber may be constructed as shown in Fig. 3, a roller 13 being mounted upon the bottom wall of the chamber for supporting the clay column and permitting the veneer to pass entirely under the same.

A sizing die 14 is provided at the outer side of the lower portion 11 of the veneer chamber, through which the clay column passes, this die controlling the thickness of veneer upon the clay column. By increasing or decreasing the size of sizing die used at this point, the veneer coating may be made thicker or thinner as desired.

For the purpose of maintaining a uniform pressure upon the veneer material, a plunger 15 may be slidably mounted in the chamber 9 and adapted to bear upon the clay or other substance used for veneering.

This plunger may be connected as by a connecting rod 16, to an intermediate portion of the lever 17, one end of which is pivoted as at 18 to a stationary object such as the bracket arm 19 and a slidale weight 20 is adapted to be mounted upon the other end portion of the lever.

By adjusting the position of this weight, any desired amount of pressure may be placed upon the veneering material and with any fixed adjustment of the weight it will be seen that the pressure will remain uniform.

It is understood that attempts have been made in the past to apply a veneer coating upon bricks but it is not known that any of

such attempts have been entirely successful and this is believed to be caused by varying pressure being applied to the veneering material. It has been found by experience that 5 by maintaining a uniform pressure upon the veneering material very satisfactory results have been produced.

It should be understood that the invention consists broadly in providing means for maintaining a uniform pressure upon the veneering material in order that a uniform and even coating of veneer may be applied to the clay column and the apparatus shown in the accompanying drawing and above described is 10 for the purpose of illustration only and does not disclose the only method by which this uniform pressure may be produced.

The veneering material may be formed of the same kind of clay of which the clay 20 column is formed, being, however, ground finer and mixed to a slightly thinner consistency than the clay column, or any other suitable substance may be used for this purpose.

25 I claim:

1. A brick veneering apparatus including means for forming a clay column, a chamber through which the column is passed, said chamber adapted to contain veneering material, and means movable within said chamber for maintaining a uniform pressure upon the veneering material in the chamber.

2. A brick veneering apparatus including means for forming a clay column, a chamber through which the column is passed, said chamber adapted to contain veneering material surrounding the column, and means movable within said chamber for maintaining a uniform pressure upon the veneering 40 material in the chamber.

3. A brick veneering apparatus including means for forming a clay column, a chamber through which the column is passed, said chamber adapted to contain veneering material, means movable within said chamber for maintaining a uniform pressure upon the veneering material in the chamber, and a sizing die through which the veneered column is passed.

40 4. A brick veneering apparatus including means for forming a clay column, a chamber through which the column is passed, said chamber adapted to contain veneering material, means movable within said chamber for maintaining a uniform pressure upon the veneering material in the chamber, and means for controlling the thickness of the veneer coating.

60 5. A brick veneering apparatus including means for forming a clay column, a chamber through which the column is passed, means for feeding veneering material to said chamber, a plunger in the chamber for forcing 65 the veneering material around the column,

and means for maintaining a uniform pressure upon the plunger.

6. A brick veneering apparatus including means for forming a clay column, a chamber through which the column is passed, means 70 for feeding veneering material to said chamber, a plunger in the chamber for forcing the veneering material around the column, means for maintaining a uniform pressure upon the plunger, and means for adjusting the pressure of the plunger.

7. A brick veneering apparatus including means for forming a clay column, a chamber through which the column is passed, said chamber adapted to contain veneering material, means for spacing the bottom of the column from the bottom of the chamber, and means for forcing the veneering material entirely around the column.

8. A brick veneering apparatus including means for forming a clay column, a chamber through which the column is passed, said chamber adapted to contain veneering material, a roller for holding the under side of the column spaced from the bottom of the chamber, and means for forcing veneering material entirely around the column.

9. A brick veneering apparatus including means for forming a clay column, a chamber through which the column is passed, said chamber adapted to contain veneering material, the sides of the chamber being inclined toward the column, means for spacing the lower side of the column from the bottom of the chamber, and means for forcing the veneering material around the column.

In testimony that I claim the above, I have hereunto subscribed my name.

ENOS A. STEWART.
